UNITED STATES PATENT OFFICE.

GEORGE H. WILLIAMS, OF BOSTON, MASSACHUSETTS, ASSIGNOR TO BOSTON CLIP AND TAG COMPANY, OF BOSTON, MASSACHUSETTS, A CORPORATION OF MASSACHUSETTS.

MACHINE FOR ATTACHING LAUNDRY TAGS.

1,426,330.

Specification of Letters Patent. Patented Aug. 15, 1922.

Application filed April 17, 1920. Serial No. 374,566.

To all whom it may concern:

Be it known that I, GEORGE H. WILLIAMS, a citizen of the United States, and a resident of Boston, county of Suffolk, and State of 5 Massachusetts, have invented an Improvement in Machines for Attaching Laundry Tags, of which the following description, in connection with the accompanying drawings, is a specification, like characters on 10 the drawings representing like parts.

This invention relates to a machine adapted to clinch markers, tags or similar articles upon objects and in particular to attach laundry tags to articles of clothing. The 15 particular form of machine here shown as an example of the invention is adapted to be used for securing the type of tag shown in my Patent 1,292,198, dated January 21, 1919, the tag shown in that patent being in the 20 form of a cloth covered channel, the flanges of which are clinched down over the edge of the article of clothing to be marked.

My invention will best be understood by reference to the following description of the 25 specific embodiment thereof which I have shown by way of example in the accompanying drawings, wherein:

Fig. 1 is a plan view of the machine;

Fig. 2 is a front elevation;

Fig. 3 is a side elevation;

Fig. 4 is a horizontal section on an enlarged scale and is on the line 4—4 of Fig. 5;

Fig. 5 is a vertical section on the lines 5—5 of Figs. 4 and 6;

Fig. 6 is a vertical section on the line 6—6 of Fig. 5, but with certain parts in elevation;

Fig. 7 is a section on the line 7—7 of Fig. 5;

Fig. 8 is a section on the line 8—8 of Fig. 6;

Fig. 9 is a fragmentary view of an article of clothing with a tag attached thereto; and

Fig. 10 is a perspective view of one of the 45 tags on a large scale.

As has been stated the particular form of machine shown in the accompanying drawings is adapted to apply the form of tag 11 shown in Fig. 10 and consisting of a channel shaped plate of flexible metal provided 50 with a cloth covering on which a notation

may be written in ink. This tag 11 is adapted to be attached to an article of clothing 13 (see Fig. 9) by having the flanges of the channel placed over the edge of the article 55 and bent down in clinching relation thereon.

The machine herein shown embodies a suitable casing 15 (Figs. 1, 2 and 3) which may be provided along the front with a projecting rib 17 cut away at 19 (Figs. 2, 3 and 6) to provide an opening unobstructed from three sides into which the edge of an article of clothing may be introduced to have the channel clinched thereon. The portion of the rib above this opening forms a clinching 65 anvil and slidably mounted in the portion below (see Fig. 6) is the clinching plunger 21 normally pressed down to the position shown by the spring 23. A lever 25 is pivoted on the shaft 27 extending transversely 70 of the casing and an end projects rearwardly of the casing and may be connected to a suitable handle or treadle, not shown, by which the lever may be rocked against the force of spring 29 and brought into contact with the lower end of clinching plunger 21 to force the same upwardly against the force of spring 23 and towards the anvil. A suitable stop 30' (Fig. 5) limits the return movement 80 of the lever under the action of the spring 29. It will be understood that if one of the tags 11 is in position with its flanges between the top of the plunger and the anvil and its flanges directed outwardly or towards the left in the figure so that they may 85 receive the edge of the article of clothing between them that the channel will, by the action of lever 25 and plunger 21, be compressed and clinched on the edge of the article. In the example shown the face plunger 21 and the portion of the rib 17 directly to the rear thereof are somewhat depressed 90 as shown at 30 in Fig. 6. There is thus provided at the front and both sides of the plunger guide surfaces which cooperate to 95 position the tag, the latter entering the depressed portion from the rear and coming to rest directly over the plunger, the front wall of the depression providing a stop and the side walls guides.

In the present embodiment of the invention the tags are fed to the machine through

a suitable race-way 31 shown at the right in Fig. 6 forming a magazine for a supply of tags. Herein the tags are adapted to be picked from the boxes in which they are packed by means of a comb 33, which descriptive word in connection with the illustration in Fig. 6 will sufficiently indicate its construction, it being a plate of sheet metal having the teeth 34 over which the channels are adapted to fit with their flanges pointing inwardly as shown. The channels are packed in the boxes in rows with their flanges abutting and their open side up. The comb is pressed down over the row and the teeth 34 enter the channels slightly spreading the same and they remain sticking on the teeth. A suitable guideway 35, the upper portion of which intersects and communicates with the race-way 31 (see Fig. 7), receives the back of the comb which can gravitate downwardly therein, being temporarily supported by the ends of the channels which project at either side thereof and make contact, in the machine shown, with an inward extension 37 of the lower portion of guide 35, which extension forms a bottom for the race-way. The end of the race-way is spaced from this supporting extension 37, as is best shown in Fig. 3, to provide a space for the operation of an element 55 hereafter to be described. As the channels are removed one by one from the comb it drops downwardly and presents a new channel at the lower end of the race-way 31. This method of supplying the channels to the machine not only facilitates their removal in proper order from the box in which they are packed but assures that they are always delivered to the machine in the same relative position, in the present instance with their flanges pointing outwardly away from the center of the machine.

As indicated by Fig. 6, the bottom 37 of the race-way 31 may be substantially at the level of the bottom of the recess 19 wherein the channels are clinched and suitable means are provided for removing the channels from the comb and delivering them to the clinching point and in the present instance it is necessary to turn these channels end for end so that the flanges will point outwardly to the left as they are delivered to the clinching point so that an article of clothing may be inserted in the recess 19 between the flanges of the channel which may then be clinched thereon.

The transfer means here illustrated embodies a suitable rotatable turret suspended by pivot pin 39 from the cover plate 41 of the casing and the turret here shown embodies a plate 43 from which depend pillars 45 carrying an opposed annular plate 47 mounted as illustrated with provision for movement relatively to the plate 43. In the transfer the channels are received between the

plates 43 and 47 and provision is made for suitable radial pockets to position the channels and these may be provided for by forming the plate 47 as herein with alternate raised and depressed portions, the raised portions defining between them pockets to receive the channels. Also carried by the pillars 45 and located beneath plate 47 is a similar annulus 49 having alternately raised and depressed portions as best seen in Figs. 5 and 6. The pillars 45 engage the relatively depressed portions and the raised portions make contact with the depressed portions of the plate 47 and act as springs to press it towards plate 43. It will be understood that if a channel is presented base foremost radially to one of these pockets it will wedge outwardly the plate 47 against the force of the spring and will be resiliently held in the turret. The corrugated form of plate 47 provides a local flexibility permitting this action without a loosening of the grip on channels in other pockets.

Herein, as shown in Fig. 4, four such pockets are provided and the turret is rotated intermittently, as, for example, by the means later to be described. Referring to Fig. 4, in the position of rest of the turret a tag is fed in to what is in that figure the upper pocket, then rotates to the left hand position and after another rotation is brought to the lower position in alignment with the recess 19 and is fed out from the turret into position over the plunger 21 to be clinched thereby.

I will next describe the means herein illustrated for feeding the tags from the magazine or race-way to the turret and from the turret to the clinching point. Because of certain details of mechanical construction in the example shown it will be most convenient first to describe the means for delivering the tag from the turret to the clinching point.

Referring to Fig. 4 in the present embodiment of the invention the lever 25 carries the upwardly projecting arm 51 adapted to project up through the center of the annular plate 47 which forms the bottom of the turret and provided with a hooked end or bill 53 adapted to work between the annular plates 47 and 43 and in one extreme of position to project into the recess 19 to the position shown in Figs. 4 and 6. Imagining the arm 51 to be swung clockwise from the position shown in Fig. 6, it will then be seen that the end of hook 53 is retracted inwardly within the paths of the pillars 45 and of the channels received in the pockets of the turret and the turret may then rotate freely. As the turret comes to rest the arm 51 is swung counterclockwise towards the position shown in Fig. 6 and, passing between two of the pillars as illustrated in Fig. 4, engages the

- back of the channel occupying what in Fig. 4 is the lowermost pocket and pushes it out of the turret into the recess 19 and positions it with the flanges extending outwardly between the anvil and the plunger 21. In this movement it will shove the tag into position to be clinched over the edge of any article which may thereafter be inserted in the recess 19.
- 10 The means here shown for feeding the tags from the raceway to the turret takes the form of an oscillating hook-like member 55 having a pair of tines, as best shown in Fig. 4, to permit it to swing rearwardly past the 15 guide 35 which is received between the tines. The bill portion of this hook operates substantially at the bottom of the race-way 33 and the hook 55 is here shown as carried on an arm 57 pivoted at 59 and which may be 20 operated by a link 61 connecting the arms 51 and 57. The parts being in the position shown in Fig. 6, the lowermost channel in the race-way rests with its ends on the two tines of the hook 55. The hook now swings 25 clockwise until its point clears the flanges of the channel and the latter is permitted to drop until its sides make contact with the bottom 37 for the race-way. The tines then advance on either side of the comb towards 30 the left in Fig. 6 and enter between the flanges of the channel, stripping it off the tooth of the comb and, finally advancing to the full line position of the figure, pressing it into that pocket of the turret which is 35 presented to the race-way, this being the uppermost pocket viewing Fig. 4. The plate 47 yields against the action of the spring 49 during this inserting action and the tag is firmly clinched in position in the turret.
- 40 It may be convenient at the present time to recapitulate briefly the cycle of motion of the parts. All the parts are actuated from the lever 25 shown in Fig. 4. On the down stroke of this lever the hooks 53 and 55 are 45 drawn to the right in Fig. 6 out of the way of the turret, the plunger 21 is actuated to clinch a channel and the turret is rotated, herein for a quarter of a revolution. On the return stroke or up stroke of the lever 50 the turret is stationary, the hook 55 feeds a channel from the race-way to the turret and the hook 53 feeds a channel from the opposite pocket of the turret into position over the clinching plunger 21.
- 55 I shall next describe the particular mechanism herein shown by way of example for rotating the transfer turret and in doing so shall refer particularly to Figs. 7, 8 and 6. Mounted along one side of the casing is a 60 rock shaft 63 in the form of a sleeve journaled on pin 65 which shaft may be provided with teeth 67 (see Fig. 8) with which are adapted to cooperate a tappet 69 which herein projects from the side of connecting link 61. Referring to Fig. 8, on the down
- stroke of the lever 25 tappet 69 moves towards the right, engages the right hand tooth and rocks shaft 63 towards the rear of the casing. On the return stroke it engages the left hand tooth and returns the shaft to 70 initial position.
- A suitable ratchet mechanism is utilized for intermittently driving the turret from the rock shaft 63. As best shown in Fig. 7, the turret may be provided with suitable 75 trundles projecting from the upper side thereof and forming a pin gear and a suitable intermittent driver may be utilized to drive the pin gear from the rock shaft 63. I have herein shown a pair of segmental ears 73 formed integral with the shaft 63 and projecting inwardly over the turret and between these ears is pivoted a pawl 75 adapted to engage the trundles 71.
- In Fig. 7 the parts are shown in their 85 position of rest with the lever 25 at the end of its return stroke as in Fig. 6. On the down stroke tappet 69 causes the shaft 63 to rotate clockwise, viewing Fig. 7, and pawl 75 engaging the upper right hand 90 trundle 71 in that figure partially rotates the turret, the spring pressed retaining dog 77 on the opposite side yielding in well known manner to permit this movement. As the trundle, which in Fig. 7 is in the 95 lower right hand position, approaches the horizontal it is engaged by the semi-circular recesses 79 in the segments 73 and as the pawl 75 becomes ineffective to drive the turret these recesses take up the work still 100 further to advance the turret and as they move out of cooperation with the trundle the turret has completed a quarter of a revolution, the retaining dog 77 snaps in behind the first trundle and the parts are 105 in position to permit the rock shaft to be swung backwardly, counterclockwise in Fig. 7, to the position shown in that figure, this movement being an idle movement without rotation of the turret.
- I have described in detail the mechanical construction of the machine shown as an example of my invention in the accompanying drawings not because all the details of construction are essential but in order 110 that the illustrative embodiment might be readily understood and the fundamental principles exemplified thereby be easily comprehended. These principles which I consider new and desire to secure by Letters 115 Patent I shall express in the following claims.
- Claims:
1. A machine of the class described comprising a clinching mechanism embodying 125 an anvil and an opposed plunger, a magazine, a turret interposed between said clinching mechanism and magazine, a lever for operating the plunger and arms connected therewith for delivering tags from 130

the magazine to the turret and from the turret to the anvil.

2. A machine of the class described comprising a clinching mechanism embodying 5 an anvil and an opposed plunger, a magazine, a turret interposed between said clinching mechanism and magazine and an oscillating linkage for operating the plunger and including an arm for delivering tags from the magazine to the turret and from the turret to the anvil and also embodying a tappet to impart intermittent rotary movement to the turret.

3. A machine for applying channels comprising 15 a clinching mechanism, a comb having teeth for supporting the channels and means including mechanism for reversing the position of the channels for delivering them from said comb to the clinching mechanism.

4. A machine of the class described comprising a casing having a transverse opening permitting the introduction of work, a clinching plunger intersecting the opening, a turret suspended from the top of the casing for delivering tags to said opening and a plunger-operating lever received in the casing beneath said turret.

5. A machine of the class described comprising 30 a casing having a transverse opening permitting the introduction of work, a clinching plunger intersecting the opening a turret suspended from the top of the casing for delivering tags to said opening, a plunger-operating lever received in the casing beneath said turret, means for intermittently rotating the turret including a laterally disposed swinging member and means for transmitting movement from said 40 lever to said member.

6. A machine of the class described comprising a casing having a transverse opening permitting the introduction of work, a clinching plunger intersecting the opening, a turret suspended from the top of the casing for delivering tags to said opening, a pin gear on the turret, a laterally disposed rock shaft having a projecting arm having provision for engaging and driving said 45 gear in one direction, a plunger-operating lever received in the casing beneath the turret and means for transmitting movement from said lever to said member.

7. A machine for applying channels comprising 55 a clinching mechanism, a supply device comprising a comb having teeth over which the channels fit, a device having tines for engaging a channel and stripping it from the teeth and transfer means for receiving the channel and delivering it to the clinching mechanism.

8. A machine for applying channels comprising 60 a clinching mechanism, a supply device comprising a comb having teeth over which the channels fit, a device having tines

for engaging a channel and stripping it from the teeth and transfer means for receiving the channel and delivering it to the clinching mechanism having provision for turning it end to end.

70

9. A machine for applying channels comprising a clinching means, a turret aligned therewith comprising a plate and an opposed annular plate and pillars spacing said plates to receive the channels therebetween, and means for delivering channels from the turret to the clinching means comprising a hooked arm projecting through the annular plate.

75

10. In a machine for applying channels 80 the channel transfer means comprising a turret which embodies a plate, an opposed annular plate and pillars spacing said plates to receive the channels therebetween and means for delivering channels to and from 85 said turret comprising swinging arms having ends working between said plates, one of said arms projecting through the annular plate.

85

11. In a machine of the class described 90 the combination with clinching means and supply means, of the transfer turret including a plate and an opposed plate yieldably mounted in spaced relation thereto.

12. In a machine of the class described the 95 combination with clinching means and supply means, of the transfer turret including a plate and an opposed plate having alternating segmental raised and depressed portions providing pockets, said opposed plate 100 being yieldably mounted in spaced relation to the first.

13. In a machine of the class described the combination with clinching means and supply means, of a transfer turret including 105 a plate, pillars carried thereby, an opposed plate having provision providing in cooperation with said first plate spaced radial pockets and movably carried on the pillars, and an annulus carried by said pillars having spring portions opposite said pockets to press said second plate toward the first.

110

14. In a machine of the class described the combination with clinching means and supply means, of a transfer turret including a 115 plate, pillars carried thereby, an opposed plate having alternating segmental raised and depressed portions providing pockets and movably carried on the pillars, and an annulus carried by said pillars having spring portions opposite said pockets to press said second plate toward the first.

120

15. A machine of the class described comprising a clinching mechanism, a transfer device at one side thereof, a feeding means 125 comprising a strip formed to support channels on its edge, means for supporting the strip adjacent the transfer device, a hooked arm having tines operating on opposite sides of the strip to deliver channels to the 130

transfer device, a swinging arm to deliver channels from the transfer device to the anvil and means for operating said arms in alternation with the clinching means.

5. 16. In a machine as described the transfer means including a turret, trundles thereon, a rock shaft disposed laterally of said

turret, a sector thereon having a notch to receive the trundles and a pawl carried by the sector in advance of the notch. 10

In testimony whereof, I have signed my name to this specification.

GEORGE H. WILLIAMS.
